UNITED STATES PATENT OFFICE.

OLIN W. KENNEDY, OF MUNCIE, INDIANA.

DESIGN FOR A DISPLAY-FRAME.

SPECIFICATION forming part of Design No. 36,285, dated April 14, 1903.

Application filed January 14, 1903. Serial No. 139,081. Term of patent 3½ years.

To all whom it may concern:

Be it known that I, OLIN W. KENNEDY, a citizen of the United States, residing at Muncie, county of Delaware, and State of Indiana, 5 have invented and produced a new, original, and ornamental Design for Display-Frames, of which the following is a specification, reference being had to the accompanying drawings, forming a part thereof.

10 In the accompanying drawings, Figure 1 is a side elevation showing my design for display-frames. Fig. 2 is an edge view of my frame.

15 As shown in the drawings, the leading or material feature of my design consists of a frame 1, having ornamental border 2, said

frame being provided with plain surfaces 3, 4, and 5, each of said surfaces being surrounded by an ornamental scrollwork 6.

Having described my invention, what I 20 claim as new, and desire to secure by Letters Patent, is—

The ornamental design for a display-frame as herein shown and described.

In testimony whereof I have hereunto 25 signed my name to this specification in the presence of two subscribing witnesses.

OLIN W. KENNEDY.
